Patented April 11, 1905.

UNITED STATES PATENT OFFICE.

MAX R. LEHMAN, OF QUINCY, ILLINOIS, ASSIGNOR TO EXCELSIOR STOVE & MANUFACTURING COMPANY, OF QUINCY, ILLINOIS, A CORPORATION.

DESIGN FOR A STOVE.

SPECIFICATION forming part of Design No. 37,401, dated April 11, 1905.

Application filed March 6, 1905. Serial No. 248,775. Term of patent 7 years.

To all whom it may concern:

Be it known that I, MAX R. LEHMAN, a citizen of the United States, residing in Quincy, in the county of Adams and State of Illinois, have invented a new, original, and ornamental Design for Stoves.

The accompanying drawing, which is a perspective view, illustrates my new, original, and ornamental design for a stove.

I claim—

The ornamental design for a stove, as shown.

MAX R. LEHMAN.

In presence of—

ANTON OHNEMUS,
GEORGE P. SWEETRING.
